GAME

Filed Feb. 8, 1927

By John W. Farley
Attorney

UNITED STATES PATENT OFFICE.

ANDREW E. BIRD, OF MEMPHIS, TENNESSEE.

GAME.

Application filed February 8, 1927. Serial No. 166,703.

The invention relates to games, particularly games wherein a marble is shot towards a partition having a plurality of independent compartments behind the partition, and apertures in the partitions through which the marble is adapted to be shot, which apertures have indicia of different values of gain or loss, which game may be played by any number of persons, the person first obtaining a predetermined score being the winner.

A further object is to provide a yieldable member in the compartments behind the partition, and against which a marble engages and passes in the compartments, thereby increasing the hazard of a rebound through the partition opening, and increasing the loss of the player.

A further object is to form the yieldable member from a single piece of material, for instance rubber, the ends of which are anchored to opposite sides of the game board and extend through aligned apertures in the members forming the divisional walls between the compartments.

A further object is to provide a central aperture which has a lose value adjacent higher values, thereby increasing the hazard of a player attempting to make the higher values.

A further object is to provide a surface projectile game board comprising side walls, an apertured partition connecting said side walls and a plurality of chambers behind the partition.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a plan view of the game board.

Figure 2 is a vertical transverse sectional view through the game board taken on line 2-2 of Figure 1.

Figure 3 is a detail perspective view of one corner of the game board.

Referring to the drawing the numeral 1 designates the game board, which board comprises side walls 2 and end walls 3 and 4.

Extending transversely of the game board

and spaced from the rear wall 4 is a vertically disposed partition 5, which partition is provided with a plurality of apertures 6, through which players project marbles, and it will be noted that the apertures 6 have 60 indicia adjacent the same of different value, and in playing the game any number of players may play, however a predetermined score is set to indicate the winner and the first player to obtain the predetermined 65 score is considered the winner. The central aperture or opening 6 is an aperture which indicates a loss when a marble goes through the same, and it will be noted it is disposed adjacent the opening 6 having the highest 70 value, thereby increasing the hazard of players attempting to make the higher values, and as the other apertures have a lower value, are spaced a substantial distance from the central lose aperture, the risk in trying 75 to make these values is relatively low. The central aperture 6 may be made larger or smaller for varying the hazard. Extending rearwardly from the rear side of the partition 5 are spaced walls 7, which form the 80 compartments into which the marbles pass when they are accurately projected through the apertures 6. To further increase the hazard the transversely disposed yieldable member 8 is provided, the ends of which are 85 anchored at 9 to the side walls and extend through apertures 10 in the walls 7, and which yieldable member is preferably formed from rubber, however it is to be understood that a relatively narrow coiled 90 spring may be used if desired. If during the playing of the game a marble enters a compartment and engages the yieldable member 8 and rebounds through the aperture, this will constitute a loss equal to the indicia of 95 the particular aperture through which the marble enters, therefore it will be noted that considerable skill is required to play the same and the hazards are great.

The yieldable member 8 which is preferably formed from rubber is slightly stretched when anchored at 9 to the side walls 2, and by passing the same through the apertures 10, it will be noted it will have a relatively wide range of stretch for projecting the marbles forwardly towards the apertures 6. However during the playing operation it will require considerable skill for a player to project a marble through the aperture, either at speed or an angle whereby it 110

will not rebound through the entrance aperture. By forming the yieldable member 8 from a single piece of material, it is obvious the cost of manufacture is materially reduced and this member can be easily renewed if the same breaks by simply stretching a rubber strip through the apertures 10 and anchoring the ends thereof at 9. Although a forward portion is shown over which the marbles roll it is to be understood this may be eliminated and the surface of a table or floor used for this purpose. It is also to be understood that the rules may be varied as desired.

From the above it will be seen that a game is provided of the surface projectile type, which game is simple in construction, may be cheaply manufactured and sold, and one wherein the hazards are relatively great,

thereby developing considerable skill and 20 learning and playing the game.

The invention having been set forth what is claimed as new and useful is:—

The combination with a game board having an apertured partition in the apertures of which marbles are projected into chambers, a plurality of partitions behind the partition and forming the chambers, of a yieldable stretchable marble rebound member extending through said chambers, said rebound member being anchored to opposite sides of the game board and extending through apertures in the plurality of partitions.

Signed at Memphis in the county of 25 Shelby and State of Tennessee, this 18th day of January A. D. 1927.

ANDREW E. BIRD.
